UNITED STATES PATENT OFFICE.

WENSEL TUMA AND MARTIN TUMA, OF NEW PRAGUE, MINNESOTA.

TRACTOR-GOVERNOR.

1,340,993.

Specification of Letters Patent. Patented May 25, 1920.

Application filed May 8, 1919. Serial No. 295,813.

To all whom it may concern:

Be it known that we, WENSEL TUMA and MARTIN TUMA, citizens of the United States, residing at New Prague, in the county of Lesueur and State of Minnesota, have invented certain new and useful Improvements in Tractor-Governors; and we do declare the following to be a full, clear, and exact description of the invention, such as will enable others skilled in the art to which it appertains to make and use the same.

Our invention relates to improvements in governors and more particularly to a novel device for attachment to tractors of the Fordson type, and the object of the invention is to provide a device of this character which may be inexpensively manufactured and marketed, easily installed, and used to great advantage for controlling the speed of the motor either when the tractor is pulling a load or when it is operated as a stationary engine for driving numerous kinds of machines. We have found that without the use of the improved governor, the motor speed varies according to the resistance of the load and the motor often chokes. Furthermore, racing of the motor takes place when starting. By the provision of the improved governor, however, these difficulties are overcome and the machine will operate at a uniform speed regardless of the manner in which the resistance of the load may vary.

With the foregoing in view, the invention resides in the novel construction and arrangement of parts, hereinafter described and claimed, reference being made to the accompanying drawings.

Figure 1 is a perspective view of a part of the tractor showing the form of our invention.

Fig. 2 is an enlarged vertical section of the governor.

Fig. 3 is a perspective view of the governor bearing and attaching bracket.

Fig. 4 is a perspective view of the tubular shaft of the governor.

Fig. 5 is a detail vertical section showing the manner of mounting the bell crank upon the motor.

In the drawings, the numeral 1 designates the motor of a Fordson tractor; 2 has reference to the carburetor whose operation, except when starting, is controlled by the longitudinal rock shaft 3; 4 refers to the fan belt; 5 indicates the radiator; and 6 designates the rearwardly extending header of said radiator. These parts are briefly described for the purpose of more clearly explaining the present invention, but it will be understood that they are all well known in the art.

A vertical arm 7 is provided with a flange 8 at its upper end which is secured by cap screws 9 or other preferred means to the bottom of the header 6, and the lower end of said arm carries a horizontal bearing 10 which extends longitudinally of the machine. Rotatable in the bearing 10 is a tubular shaft 11 having on its front end a grooved pulley 12, which is driven by a belt 13 from a similar pulley 14 which is in turn driven by the fan belt 4. The rear end of shaft 11 is provided with a head 15 to which governor arms 16 are fulcrumed, said arms having weights 17 adapted to be thrown outwardly by centrifugal force, against the tension of coil springs 18.

A short thrust rod 19 is located in the rear end of the shaft 11 and through the instrumentality of a bearing-ball 20, said rod thrusts against a longer thrust rod 21 which is positioned in and projects forwardly from the shaft 11. The front end of rod 21 is bent downwardly to provide a depending arm 22 and is then extended rearwardly to form a control rod 23 which is positioned above the motor 1 and may well slide through a guide 24. The rear end of rod 23 is pivoted to one arm of a bell crank 25, while an adjustable link 26 connects the other end of said bell crank with a crank 27 which is clamped by a bolt or the like 28 upon the rock shaft 3.

The bell crank 25 is fulcrumed on the upper end of a stud 29 which is tapped into one of the cap screws 30, which screw holds the cylinder head of the motor in place. By mounting the bell crank upon one of the cap screws 3, when these screws are removed to detach the cylinder head, the bell crank is simultaneously detached. Furthermore, this mounting does not necessitate weakening of any part of the motor by drilling holes therein for attaching screws or the like.

In operation, the belt 13 drives the pulley 12 and the latter in turn operates shaft 11. If the tractor is meeting little resistance and the motor has a tendency to run faster than desirable, the weights 17 are thrown outwardly by centrifugal force, with the result that the push rod 19 and the ball 20

thrust forwardly on the rod 21, shifting the control rod 23 forwardly. This operates the bell crank 25, link 26 and crank arm 27 in such a manner as to turn the carbureter control shaft 3 in a direction to diminish the fuel supply. When the tractor is operating under a heavy load or resistance, and the motor is therefore running at a comparatively low speed, the springs 18 overbalance the centrifugal force acting on the weights 17 and thus the governor is not operated to cut down the fuel supply, but on the other end the throttle is allowed to remain open to the required extent.

15 From the foregoing, taken in connection with the accompanying drawings, it will be seen that although our invention is of extremely simple and inexpensive nature, and may be easily attached to the tractor, it 20 will be highly efficient in governing the motor speed, both when the machine is used for traction purposes and as a stationary engine. Since probably the best results are obtainable from the details shown and described, and by attaching the several parts in the manner disclosed, these features are 25 preferably followed, but we wish it understood that within the scope of the invention as claimed, considerable latitude is allowed 30 for making numerous minor changes.

We claim:

1. In a governing device for tractors, the combination with the tractor motor having a forwardly extending rotary shaft, a carbureter, and a rock shaft for extending longitudinally of the motor for controlling said carbureter; of a centrifugal governor mounted adjacent the front end of said motor and driven from said rotary shaft, a rod 35 parallel with said rock shaft and longitudinally shiftable by said governor, and means connecting said rod and rock shaft for turning the latter from the former.

2. In a governing device for tractors, the combination with the tractor motor having a forwardly extending rotary shaft, a carbureter, and a rock shaft extending longitudinally of the motor for controlling said carbureter; of a bearing mounted adjacent 45 the front end of said motor, a tubular shaft in said bearing extending longitudinally of

the motor and driven from said rotary shaft, a push rod mounted slidably in said tubular shaft, a weighted governor arm carried by the rear end of said tubular shaft for shifting said push rod, an arm rigidly depending from the front end of said push rod in advance of said tubular shaft, a control rod parallel with said rock shaft and extending rearwardly from the outer end of 55 said arm, and means connecting said control rod and said rock shaft for operating the latter from the former.

3. The combination with a tractor motor having a forwardly extending rotary shaft, a carbureter, and a control member for said carbureter, said motor having a detachable cylinder head secured in place by cap screws; of a centrifugal governor driven by said rotary shaft, a bell crank mounted on one 60 of said cap screws, means for operating said bell crank from said governor, and means connecting said control member with said bell crank.

4. A governing attachment for tractors 75 comprising a pulley adapted to be driven by the usual fan belt pulley, a bearing having an attaching bracket for mounting it longitudinally at the front end of the motor, a tubular shaft rotatable in said bearing 80 and carrying a pulley on its front end, a belt driving said last named pulley from the aforesaid pulley, a weighted governor arm mounted on the rear end of said tubular shaft, a push rod slidably in said tubular 85 shaft and operated by said governor arm, a lateral arm extending rigidly from the front end of said push rod, a control rod parallel with said rock shaft and extending rearwardly from the outer end of said arm, a 90 bell crank connected at one end with the rear end of said control rod, a link extending from the other end of said bell crank, a crank arm connected to said link and adapted for attachment to the carbureter 95 control shaft, and means for fulcruming said bell crank on the tractor motor.

In testimony whereof we have hereunto set our hands:

WENSEL TUMA.
MARTIN TUMA.
